(57) **CLAIM**

The ornamental design for a solder feed iron, as shown and described.

DESCRIPTION

FIG. 1 is a perspective view of the solder feed iron.

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a perspective view of a second embodiment of the solder feed iron.

FIG. 9 is a front view of the second embodiment thereof;

FIG. 10 is a rear view of the second embodiment thereof;

FIG. 11 is a left side view of the second embodiment thereof;

FIG. 12 is a right side view of the second embodiment thereof;

FIG. 13 is a top view of the second embodiment thereof; and,

FIG. 14 is a bottom view of the second embodiment thereof.

The broken lines in figures are to show unclaimed subject matter and form no part of the claimed design.
